UNITED STATES PATENT OFFICE

THOMAS O'NEILL, OF BROOKLYN, NEW YORK, ASSIGNOR TO THE SINGER MANUFACTURING COMPANY, OF ELIZABETH, NEW JERSEY, A CORPORATION OF NEW JERSEY

BINDER FOR SEWING MACHINES

Application filed March 15, 1929. Serial No. 347,206.

This invention relates to improvements in binders of the strip-reversing type, which, when applied to a sewing machine, are disposed crosswise of the line of seam formation and are provided with spaced delivery lips oblique to the binder length.

Binders of this type are employed to apply a binding-strip upon a body material margin passed between the delivery lips of the binder in a direction substantially transverse to the direction of passage of a binding strip through the binder. As the delivery end of the binder is of course disposed in advance of the needle-path, it has heretofore been difficult to satisfactorily secure the binding-strip when applying it to work margins having reentrant-angles. This difficulty increases with the width of the binding employed, because the front side of the inner fold-forming or binding doubling rib of the binder is necessarily spaced increasingly farther from the needle with increases in the width of the binding and it is this folding rib which is engaged by the unbound side of the work-angle and therefore interferes with the feeding of the work to effect stitching thereof to substantially the vertex of the angle. Consequently, in turning the work to bind an internal corner thereof, the needle is liable to entirely miss the body material and the binding bridges the corner instead of being snugly fitted thereto.

The present invention aims to overcome the described difficulty and to provide means permitting binding-strips to be snugly applied to the corners of reentrant-angles and scalloped work-margins, with the stitching securely anchored in the body material.

In a preferred embodiment of the invention which is more particularly adapted for binding comparatively stiff body materials such as leathers or imitation leathers, the fold-forming rib of the binder employed for doubling the binding-strip longitudinally is provided with a recess extending lengthwise of said rib and terminating in the delivery end of the binder.

This construction permits the unbound side of the work-angle to enter the rib-recess

to a point substantially abreast of the needle, whereupon the work may be turned about a point-contact edge-guide at the rear side of the binder. The entering of the body material into the rib-recess necessarily indents the binding-strip and to assist in taking up this indentation after the turning of the work, there is provided a spring tongue of which the free end extends through the mouth of the rib-recess and may yield, under the pressure of the unbound side of the work-angle during the feeding of the work, to complete the stitching to a point substantially abreast of the work corner. The indenting of the binding-strip draws in the edges thereof and has the effect of taking up slack in the binding formed by turning the work and therefore the edges of the binding are nicely rounded at the corner, while its middle portion is snugly fitted into the corner. The rearwardly yielding movement of the spring tongue is limited by a suitable stop-member at the rear side of the binder, which stop-member functions as an edge-guide for the body material during the binding of straight runs thereof. The spring tongue preferably extends beyond the guiding edge of said stop-member, whereby the free end of said tongue may function as a guide for the work when turning the same to stitch a corner.

In the accompanying drawings, Fig. 1 is a front side elevation of the improved binder and of a portion of a sewing machine to which it has been applied. Fig. 2 is a rear side elevation of the binder. Fig. 3 is a vertical section substantially on the line 3-3 of Fig. 2. Fig. 4 is a top plan view of a portion of the sewing machine cloth-plate and attached binder. Fig. 5 is a horizontal section substantially on the line 5-5 of Fig. 2. Fig. 6 shows a portion of bound reentrant-angle work and in dotted lines the delivery end of the binder to illustrate the position of the spring tongue just before the corner is turned.

Referring to the drawings, the present improvement is shown as embodied in a sewing machine having a cloth-plate 1 and an overhanging bracket-arm terminating in a head 2. Suitably secured upon the cloth-

plate is a throat-plate 3 which is slotted to receive a feed-dog 4 of the lower four-motion type and is apertured to permit reciprocation therethrough of a needle 5. The needle 5 is carried by a needle-bar 6 journaled for endwise reciprocation in a vibratory frame 7 supported by the head 2 in a manner (not shown) to provide for work-feeding movements of the needle, i. e., lateral movements of the needle in the direction of and with the work-advancing movements of the feed-dog 4.

Opposed to the feed-dog 4 is a presser-foot 8 carried by a presser-bar 9, and a feeding-foot 10 carried by a feed-bar 11, the presser-foot 8 and the feeding-foot 10 being alternately raised and lowered. The feeding-foot also assists in feeding the work and to this end, its carrying bar 11 is journaled for endwise movements in the vibratory frame 7. A combined needle and clamp-feed arrangement of this type is disclosed, for instance, in the U. S. patent to A. Rontke, No. 1,128,519, Feb. 16, 1915, and being well known in this art is believed to require no further description.

Hingedly secured upon the cloth-plate 1, by means of a pivot-screw 12, is a swing-out binder-supporting plate 13 provided on its under side with a pin 14 adapted to enter a suitable aperture in the cloth-plate to properly locate said supporting-plate in the operative position of the binder carried thereby. The supporting-plate 13 is slotted at 15 to provide a depressed wing 16 positioned in the clearance recess 17 formed in the cloth-plate 1 for retraction of the usual slide-plate 18.

Secured upon the supporting-plate wing 16 by screws, as 19, for adjustment crosswise of the line of seam formation is the shank 20 of an arm 21 sustaining a binder 22 of the strip-reversing type. In the present instance, the binder 22 is made of sheet metal bent to provide an inner fold-forming rib 23 which functions to double a binding-strip longitudinally.

The upper side member of the rib 23 terminates in a reversely bent flange 24 constituting in effect a scroll for turning in the upper edge of the binding, said flange 24 being in the present instance soldered to the under side of the supporting arm 21. The lower side member of the rib 23 also terminates in a flange 25 to provide a guiding passage for the lower edge of the binding-strip, said lower edge of the binding-strip being in the present case not inturned, as will be observed from an inspection of Fig. 6. As the present binder is designed more particularly for heavy work, it is preferred to employ further supporting means therefor. To this end, the lower flange 25 is soldered to an arm 26 adjustably secured by screws, 65 as 27, upon the supporting-plate wing 16.

The receiving end 28 of the binder is vertically disposed and is substantially flat, the binder-flanges 24 and 25 converging from said receiving end 28 toward the binder delivery end. This delivery end comprises spaced lips 29 and 30 partly cut away to provide strip-reversing edges, as 31 and 32, oblique to the length of the binder, i. e., inclined to the direction of passage of a binding-strip through the binder and also inclined to the line of seam formation. The binder is, as usual, disposed crosswise of the line of seam formation, it being preferred to position the binder so that it is slightly inclined to the line of feed, with the binder delivery end in advance of its receiving end.

The supporting-plate 13 is suitably cut away to permit positioning of the lower side of the binder substantially in the plane of the cloth-plate. To better direct the body material to be bound between the lips 29, 30 the supporting-plate 13 is provided with a raised portion 33 in advance of said lips.

In order that the unbound side of reentrant-angle work may be advanced by the feeding mechanism of the machine sufficiently far to stitch to a point substantially abreast of the corner of the work, the binding-strip doubling rib 23 is provided lengthwise thereof with a recess 34 in the front face of said rib and terminating in the delivery end of the binder between the lips 29 and 30 thereof. This recess is entered by the unbound side of the work angle, which causes the binding-strip to be indented under the action of the feeding mechanism. By positioning the binder at an angle to the line of feed as described, it is evidently unnecessary to continue the recess 34 the entire length of the binder.

Projecting into said recess 34 is a spring tongue 35, which in the present case is soldered to the rear side of the binder at the work receiving end thereof. This tongue 35 is free to yield to the passage of the work and to an extent limited by a stop-member 36 bridging the upper and lower members of the rib 23 at the rear side of the binder. The edge 37 of the stop-member constitutes an edge-guide for the binding-strip and body material in straight runs thereof and as the free end of the tongue 35 when pressed into contact with the member 36 extends slightly beyond the edge 37, the work may be swung about the point-contact afforded by the free end of the tongue when turning the corner of the work. After the work is turned, the tongue returns to its former position wherein it projects slightly through the recess 34 and in doing so, it takes up the indentation produced in the binding-strip by the entrance of the body material into said recess. This indentation of the binding-strip causes some retraction of the edges of said strip and in thus taking up the fullness thereof, the

binding may be smoothly applied to the corner.

While the sheet metal type of strip-reversing binder has been herein described in general terms, it is to be understood that the invention is equally applicable to other types of strip-reversing binders having a solid block for doubling the binding-strip longitudinally. The essential feature of the invention is the provision of means, in a strip-reversing binder, to permit feeding of the body material having reentrant-angles, or in fact scallops, to a point wherein the binding may be satisfactorily secured to internal angles and curved work.

In Fig. 6 of the drawings is illustrated a fragment of work in which a body material M, having a reentrant-angle, is bound by a binding-strip B doubled longitudinally to embrace the edge of the body material, the upper portion of the binding-strip having its free edge turned. The binding is secured by stitches S and it will be observed, by the illustration in dotted lines of the present binder delivery end, that the side A of the work-angle may be advanced in the direction of feed, indicated by the arrow, to lay the binding snugly into the corner of the work-angle.

Having thus set forth the nature of the invention, what I claim herein is:—

1. A strip-reversing binder having an oblique delivery end and an inner fold-forming rib about which a binding-strip is doubled longitudinally, said rib being provided lengthwise of the binder with a recess in its front face terminating in the delivery end of the binder.

2. A strip-reversing binder having an oblique delivery end, an inner fold-forming rib for doubling a binding-strip longitudinally, said rib being provided lengthwise of the binder with a recess in its front face terminating in the delivery end of the binder, and a yielding tongue disposed in said recess.

3. A strip-reversing binder having spaced delivery lips oblique to the binder length, a body material edge-guide between said lips disposed at substantially the rear side of the binder, and an inner fold-forming rib about which a binding-strip is doubled longitudinally, said rib being provided lengthwise of the binder with a recess in its front face terminating in the delivery end of the binder.

4. A strip-reversing binder having spaced delivery lips oblique to the binder length, a body material edge-guide between said lips disposed at substantially the rear side of the binder, an inner fold-forming rib for doubling a binding-strip longitudinally, said rib being provided lengthwise of the binder with a recess in its front face terminating in the delivery end of the binder, and a yielding tongue disposed in said recess.

5. In a sewing machine having a recipro-

catory needle and work-feeding mechanism, a binder disposed crosswise of the line of seam formation having spaced delivery lips inclined to the binder length and an inner fold-forming rib about which the binding-strip is doubled longitudinally, said rib being provided lengthwise of the binder with a recess in its front face terminating in the delivery end of the binder, and a body material edge-guide at the rear side of said binder substantially abreast of the needle, said recess providing an open passageway from the front side of the binder to said edge-guide.

6. In a sewing machine having a reciprocating needle, work-feeding mechanism, a strip-reversing binder disposed crosswise of the line of seam formation to incline forwardly from its receiving toward its delivery end in advance of the path of the needle, said binder having an inner fold-forming rib about which a binding-strip is doubled longitudinally, and said rib being provided longitudinally thereof with a recess in its front face terminating in the delivery end of the binder.

7. A strip-reversing binder having spaced delivery lips oblique to the binder length, an inner fold-forming rib provided longitudinally thereof with a recess in its front face terminating in the delivery end of the binder, a yielding tongue projecting into said recess, and a stop-member positioned to limit the rearward movement of said tongue.

8. In a sewing machine having a reciprocating needle, work-feeding mechanism, a binder disposed crosswise of the line of seam formation having spaced delivery lips oblique to the binder length and having an inner fold-forming rib about which a binding-strip is doubled, said rib being provided longitudinally thereof in its front face with a recess terminating in the delivery end of the binder, and a work-support for directing a body material in the plane of said recess.

In testimony whereof, I have signed my name to this specification.

THOMAS O'NEILL.
